UNITED STATES PATENT OFFICE.

WILLIAM H. S. WRIGHT, OF KANSAS CITY, MISSOURI.

ELECTRIC CUT-OUT.

SPECIFICATION forming part of Letters Patent No. 398,566, dated February 26, 1889.

Application filed December 20, 1888. Serial No. 294,160. (No model.)

To all whom it may concern:

Be it known that I, WILLIAM H. S. WRIGHT, of Kansas City, Jackson county, Missouri, have invented certain new and useful Improvements in Electric Cut-Outs, of which the following is a full, clear, and exact description, reference being had to the accompanying drawings, forming a part hereof.

This invention relates to an improvement in cut-outs for electric lamps, and particularly to incandescent electrolriers. In the arrangement of a system for incandescent lighting it is necessary to provide means for relieving a loop from a main-line wire (that conveys current into a series of incandescent electrolriers) of excess of current occasioned by impediments on the line or any other cause, as, if such provision is not made, there is danger of burning up the carbon filaments in a number of electrolriers; or the insulation which prevents contact of the loop with combustible wood-work in a building may be destroyed by the excess of electricity and a disastrous conflagration result. The usual means provided to prevent injury resulting from an excess in the current of electricity on a main conductor-wire, or any loops in connection with the same, is to introduce rheostats or "current-absorbers" at different points on the line or its branches. These devices are cumbersome, complicated, and expensive, and are not assuredly reliable under all conditions of service.

The best possible provision that can be effected for the safety of the electrolriers or the prevention of fire is to separate the line of conductor-wire when there is dangerous excess of electrical current or an increase of electro-motive force on the line.

The object of my present invention is to provide a simple, reliable, and inexpensive device which is introduced in the line of conductor-wire at any desired point in the form of a neat coupler, which will, when there is an abnormal increase of electro-motive force or volume of electric current thrown on a main conductor-wire or its loops, instantly separate the line and cut out the loop which supplies a series of electrolriers with current, or an individual lamp, as the case may be.

A further object is to provide a cut-out de-

vice which will not be liable to short-circuit the line or produce a ground-connection on either of the separated terminals of the conductor-wire when the line is severed.

With these objects in view my invention consists in certain features of construction and combinations of parts, which will be more fully explained in the specification, and pointed out in the claims.

Referring to the drawings, Figure 1 is a view of the base of a an electrolier, partly in section, showing two of the improved cut-out devices in position, or this may represent a main stem of a chandelier upon which are supported a cluster of electrolriers, these being omitted from the figure. Fig. 2 is a longitudinal sectional view of one of the improved cut-outs enlarged, the terminals of line-wire being also shown in connection therewith. Fig. 3 is an end view of the device. Fig. 4 is an enlarged view of one of the essential features of the cut-out device removed from the other portions of the same.

A represents a metal shell or casing, which is a cover for the leading-in wires of an electrolier, or it may be a finishing-case at the upper end of a depending stem of a chandelier, consisting of a cluster of electrolriers that are to be guarded against injury from excess of current. The leading-in wires which convey the electricity to one or a series of electrolier-lamps are represented at *a a a a* in Figs. 1 and 2. These are protected by the usual approved insulating-coating.

Where the cut-out coupling B is introduced the leading-in wire is severed, producing two ends, *c'*, (see Fig. 2,) the body of the wire being properly cleaned off, so as to afford a good conducting-surface for electricity. Upon the ends of the wires *a* the sleeves or collars *d* are slipped and made to abut against the insulating-coating *f*.

There are two elongated metal cylinders, *E* *E'*, provided, which have an axial perforation formed in them of such relative diameter that the sleeves *d* will neatly fit within them near their outer ends when the cylinders are placed over the terminal ends of the leading-in wires *a*, which ends also fit the bore of the cylinders neatly, as shown in Fig. 2.

Upon the outer surface of the cylinders *E*

E' the non-conducting enveloping jackets or shells *h* are fitted closely, and it will be noticed that the shells *h* are of such proportionate length to that of the metal cylinders E E' that they will project a short distance beyond the outer ends of said cylinders when they are in position on them. This provision will afford protection to the electrically-conducting cylinders if the ends of the wires *a* should fall upon the ground or upon an electrical conductor having contact with the ground.

The shells *h* may be made of any non-conducting material, preferably hard rubber or gutta-purcha.

15. It will be noticed in Fig. 2 that there is a connecting-piece of metal rod, *a'*, introduced within the adjacent ends of the cylinders E E'. Said rod or piece of wire is of the same diameter or gage as the leading-in wires *a a*, and 20 produces an electrical connection between the terminals of these wires when it is in proper position, as shown.

To effect the electrical junction of the leading-in wires *a a* just mentioned, the ends 25 of the connecting-piece *a'* are enveloped with ferrules or sleeves *d'*, which are of harder metal than is the rod *a'*, said rod being composed of any metallic alloy that will afford proper electrical conducting-area to a normal 30 current of electricity, while it is not of such conductivity as will pass freely a current of abnormal energy.

It is essential that the connecting-rod *a'* be fusible at a comparatively low temperature, 35 so that the heat generated from its resistance to the transmission of electricity of such abnormal quantity or high electro-motive force as would injure lamps or create fires will be great enough to melt the fusible alloy, and 40 thus separate the ends of the line-wires or leading-in wires *a a*.

I do not limit myself to any particular composite metal or alloy of metals for the manufacture of the fusible connecting-piece *a'*, as 45 there are a number of such that are available. Lead and antimony, compounded in proper proportions, will answer well for the fusible alloy. The proportions will of course depend upon the strength of current it is desired to 50 pass over the wires before the connection *a'* should melt.

In order to hold the parts intact when they

are assembled, as shown in Fig. 1, there are metal set-screws *b'* inserted in holes tapped through the wall of cylinders E E', thus permitting the ends of the screws to bear upon the sleeves or ferrules *d'*, and assure the proper retention in place of the connecting-piece or fusee *a'*, as well as proper electrical conductivity through these metal pieces.

It is important that the heads of the screws *b'* should be embedded in the insulating material of the shells *h*, thus protecting them from contact with any electrical conductor in case the fusible rod *a'* is melted and the two 65 sections of the coupler are separated, as these may fall to the ground and short-circuit the current if the heads of the screws were exposed above the insulating-shells *h h*.

At the inner or adjacent ends of the cylinders E E' a perforation, *c*, of sufficient size is formed in the shells *h* and cylinders E E', so as to provide a transverse aperture from which the melted alloy may escape in case the fusible rod *a'* is melted at any time. This will 70 remove the metallic compound and prevent it from forming an electrical connection while in a melted condition, or after cooling.

Having fully described my invention, what I claim as new, and desire to secure by Letters Patent, is—

1. An electric cut-out comprising two wires joined by a fusible connecting-rod and an enclosing insulated transversely-divided case, whereby when the fusible rod melts the wires 85 are prevented from forming a ground-connection, substantially as set forth.

2. In an electrical insulated cut-out, the combination, with the adjacent terminals of an electrical conductor - wire and ferrules 90 placed on these ends, of a fusible rod composed of metallic alloy, two cylinders having electrical conductivity, two enveloping-shells of insulating substance, two sleeves or ferrules placed on the ends of the fusible rod, 95 and set-screws which engage these ferrules and have their heads embedded in the insulating-shells, substantially as set forth.

In testimony whereof I affix my signature in presence of two witnesses.

WILLIAM H. S. WRIGHT.
